UNITED STATES PATENT OFFICE.

SIMON HUBIG, OF CINCINNATI, OHIO, ASSIGNOR OF ONE-HALF TO
CHARLES E. ROTH, OF CINCINNATI, OHIO.

DESIGN FOR A TRANSPORTABLE BANK.

No. 37,582.

Specification for Design.

Patented Oct. 24, 1905.

Application filed February 18, 1905. Serial No. 246,341. Term of patent 14 years.

To all whom it may concern:

Be it known that I, SIMON HUBIG, a citizen of the United States of America, and a resident of Cincinnati, county of Hamilton, State of Ohio, have invented a certain new, original, and ornamental Design for a transportable Bank, of which the following is a specification.

Figure 1 is a side elevation of a transport-

able bank embodying my new design. Fig. 2 is an end elevation of the same.

I claim—

The ornamental design for a transportable bank as shown.

SIMON HUBIG.
